GARMENT HANGER

Joseph E. Apostolico, 1205 Watson St., Scranton, Pa.
Filed Nov. 6, 1959, Ser. No. 851,438
1 Claim. (Cl. 223—88)

This invention relates to a novel garment hanger of the type having spaced upstanding members to engage between the leg and the cuff at one side of the leg and at opposite ends of the cuff of trousers.

The primary object of the invention is to provide a more efficient, stronger, and more easily used device of the kind indicated, whose upstanding members are bendable toward and away from each other to accommodate cuffs of different lengths, and which, when so adjusted, maintain a cuff thereon in desirably stretched condition.

Another object of the invention is to provide a device of the character indicated above wherein the upstanding members are longitudinally spaced from each other and are independently supported at related ends of a rigid coat hanger member, on extensions of the coat hanger member which serve as supports for neckties, wrist watches, and the like.

A further object of the invention is to provide, in a device of the character indicated above, upstanding members which have laterally spaced upstanding loops which can be bent toward and away from each other to accommodate cuff sides of different thicknesses and clamp cuff sides therebetween.

Other important objects and advantageous features of the invention will be apparent from the following description and the accompanying drawings, wherein, for purposes of illustration only, a specific form of the invention is set forth in detail.

In the drawings,

FIGURE 1 is a side elevation of a garment hanger of the invention, a portion being broken away and in section;

FIGURE 2 is a bottom plan view of FIGURE 1;

FIGURE 3 is a vertical transverse section taken on the line 3—3 of FIGURE 1; and,

FIGURE 4 is a fragmentary exploded perspective view, showing the manner of connection of an upstanding member to the related part of the coat hanger member.

Referring in detail to the drawings, wherein like numerals designate like parts throughout the several views, the illustrated garment hanger, generally designated 10, comprises a coat hanger member 12, of generally conventional wooden hanger form, modified in accordance with the present invention; and provided with short longitudinally inwardly directed extensions 14, on which are mounted upstanding members 16.

While the coat hanger member 12 can be made in one piece of metal or plastic, in the case of being constructed of wood, the longitudinally outwardly sloping arms 18 are joined together at their upper ends by a glued spline, as indicated at 20, for the extra strength and rigidity thereby provided, with the shank 22 of the suspension hook 24 secured through the resultant joint.

The lower or outer ends of the sloping arms 18 are specially formed as downwardly and longitudinally curved terminals 26, having terminal surfaces 28 which are disposed at slight upward and inward angles relative to the horizontal. Fixed on and extending longitudinally and inwardly from the terminals 26, are short extensions 14, which have straight horizontal portions 30 having rounded free ends 32. The other ends of the extensions 14 have upwardly and longitudinally outwardly curved terminals 34 thereon which have terminal surfaces 36 matching in angulations and in extent the terminal surfaces 28 of the terminals 26 on the outer ends of the sloping arms 18.

2

As shown in FIGURES 1 and 2, the terminal surfaces 28 and 36 are registered and are secured together in joints which include slots 38 and 40, severally in the terminals 26 and 34, with splines 42 extending therein and glued in place.

The upstanding members 16, otherwise referred to as trouser cuff clips, are made of relatively stiff and strong wire or rod, preferably of a thickness of about one-eighth inch, in one piece, the wire being bent midway between its ends to define an arcuate connecting portion 44 from whose ends rise substantially parallel and straight perpendicular inner arms 46 of inverted U-shaped loops 48. The loops 48 comprise horizontal bight portions 50 extending longitudinally and horizontally outwardly from the upper ends of the inner arms 46, and outer perpendicular arms 52 which extend downwardly from the outer ends of the bight portions 50, and merge at their lower ends in horizontal longitudinally outwardly extending and substantially parallel legs 54, which can be substantially longer than the loops 48, as shown in FIGURE 4, and have free outer ends 56.

The clips 16 are mounted on the inward ends of the extensions 14 preferably with their legs 54 on the longitudinal center lines of the extensions and secured in parallel bores 58 formed in the extensions, and with the loops 48 close to but spaced from the free ends 32, and with the loops thereby reaching above the extensions with their bight portions 50 near to but spaced downwardly from related ones of the sloping arms 18. Sufficient exposure of the legs 54 of the clips is provided so as to afford sufficient bendability of the legs, relative to the extensions, to enable bending the clips toward and away from each other for adjustment to accommodate trousers cuffs of different lengths and hold the cuffs in stretched condition.

A pair of trousers is supported on the device 10 by slipping the cuff at one end over the loop 48 at one side of a clip and the other end of the cuff over the loop 48 at the same side, of the other clip 16, so that then the leg of the trousers bears against the adjacent side of the other loops 48 of the clips and the bight portions 50 bear upwardly against the cuff bottom. With the clips adjusted, as above indicated, the outer arms 52 of the clips will bear against the ends of the cuff so as to maintain the cuff in a desired stretched condition. The loops 48 of the clips 16 can be bent toward or away from each other, in accordance with the thickness of the material of the cuff, so as to clamp the cuff between the loops, in a secure but readily releasable manner, without danger of damage to the cuff, there being no sharp corners or edges on the clips which can catch in the material of the trousers.

Objects, such as neckties, wrist watch straps, and the like, can be readily passed over the clips 16 and engaged on the extensions 14, so as to be supported in a neat, compact, and readily available manner, while a suit, including trousers, is supported on the device 10.

While there has been shown and described herein a preferred form of the invention, it is to be understood that the invention is not necessarily confined thereto, and that any change or changes in the structure of and in the relative arrangements of components thereof are contemplated as being within the scope of the invention as defined by the claim appended hereto.

What is claimed is:

A garment hanger comprising a pair of connected downwardly-divergent arms having longitudinally-spaced lower ends, short horizontal extensions fixed on and extending longitudinally inwardly from said lower ends, each of said extensions having inner ends spaced longitudinally from each other, each of said extensions being provided with parallel bores opening to the free end thereof, and upstanding trouser cuff-engaging clips mounted on said extensions, said arms being rigid and being rigidly

connected together and said extensions being rigid and rigidly connected to said lower ends, said clips being bendable toward and away from each other relative to the extensions, said clips having horizontal longitudinally-outwardly extending legs secured to the inner ends of the extensions in the parallel bores of the extensions. 5
